A. T. JOHANSON

HEATER

Filed Oct. 2, 1924

UNITED STATES PATENT OFFICE.

ADOLPH T. JOHANSON, OF CHICAGO, ILLINOIS, ASSIGNOR TO CONSOLIDATED BOILERS CORPORATION, OF BENTON HARBOR, MICHIGAN, A CORPORATION OF MICHIGAN.

HEATER.

Application filed October 2, 1924. Serial No. 741,100.

My invention pertains to features of novelty and advantage in the construction and modes of operation of heaters of various kinds, such as steam-boilers, hot-water heaters, garbage-burners, etc., and it aims to provide a structure of this general character having a liquid or gaseous fuel-burner for supplying heat and an associated or supplemental grate, or its equivalent, which may be used as a garbage or similar burner, or which may be employed for the combustion of fuel such as coal, wood, or the like.

To this end, in the preferred embodiment of the invention, I provide an efficient and satisfactory oil or gas burner, and, adjacent to this, I supply a grate which may be used to support the garbage or other refuse while it is being dried out by the heat generated at the contiguous or adjoining burner, and on which it may be consumed after it has been sufficiently freed from moisture.

Such grate may, at times, if desired, be employed for the burning of coal, coke, wood or other fuel to supplement or augment the heating action of the adjacent fluid burner, or as a substitute therefor if required.

If preferred, the liquid or gas fuel burner may be of such capacity as to provide adequate heat under all circumstances, or it may be of lesser size or power and supplemented in its heating function under extreme or unusual conditions, as weather of very low temperature, by the combustion of fuel on the nearby auxiliary grate, whereby the heating surfaces of the appliance under such circumstances are subjected to the conjoint action of both heating means.

Or, if wanted, as for instance, if it were temporarily impossible to secure fuel for the fluid fuel burner, the grate may be used alone for sustaining the solid fuel undergoing combustion.

The two heating means are so located that substantially the entire heating surfaces of the appliance are subjected to the action of the heat generated by each.

An aim of the invention is the production or provision of a novel construction of this character which is simple in structure, which operates efficiently, which needs little attention, which is unlikely to become injured or damaged in ordinary service and which may be manufactured economically.

To permit those skilled in this art to have a full and complete understanding of the in-

vention and its various structural and functional advantages, in the accompanying drawing, throughout the views of which like reference characters have been employed to designate the same parts, I have shown a preferred embodiment of the invention, but it is to be understood that the invention is susceptible of satisfactory incorporation in structures varying more or less in details of construction.

In this drawing:

Figure 1 is a longitudinal section through the heater on the line 1—1 of Figure 2, the rotary-burner being unsectioned; and

Figure 2 is a vertical cross-section on substantially the line 2—2 of Figure 1.

Referring to this drawing, it will be seen that the heater has hollow front, back, end (2) and top walls, characterized 11, 12, 13, 14 and 15 respectively, properly stayed and braced and designed to hold the water to be heated, the structure at its top having a discharge connection 16 for the delivery of the steam or hot water, as the case may be, the water admission pipe for the furnace, boiler, or heater not being shown.

Such heater, of general, upright, rectangular form is supported on a suitably-shaped base 17 divided into two compartments 18 and 19 by an intermediate wall 21 sustaining above it a hollow, division, water-containing wall 22 connected at its front and rear ends with the interiors of the corresponding vertical walls, such water wall 22 separating the lower portion of the heater into two chambers 23 and 24.

The upper part of the heater has a number of horizontal rows of hollow, water tubes or pipes 25 connecting together the interiors of the front and rear walls and designed to be directly subjected to the heat developed in the furnace or heater.

A stack or chimney 26 for the discharge of the gaseous products of combustion connects with the inner upper part of the heater, above the topmost row of tubes or pipes, through an opening 27 extended through the end-wall 13 and the latter is equipped with a door 28 which, when opened, gives access to the several tubes for cleaning or other purposes.

An upper baffle 29 rests on the top row of tubes and reaches from the end-wall 13 well over toward, but not to, the opposite end-wall 14, and a similar, somewhat shorter,

2
lower baffle 31 lies on the lowermost row of tubes and extends from the wall 14 part way toward the wall 13, the two baffles, of a width reaching from wall 11 to wall 12, forming a tortuous and circuitous passage or flue by and around the tubes from the fire or combustion chamber to the stack.

Chamber 24 and its lower compartment 19 are provided with a rotary oil-burner 32, of known construction, operated by an electric-motor 33 positioned outside of the front of the furnace or heater base, the connecting mechanism extending into compartment 19 through an appropriate opening or aperture in the front base wall.

Burner 32 has associated with it various spaced walls 34, 35 and 36 of known form, transversely filling the cross-section of the chamber 24 and unitedly or conjointly affording a passage for preheating at least some of the air flowing to the burner to sustain combustion.

The bottom of chamber 23 is equipped with a grate 37 of any suitable or approved design adapted to be shaken by an external handle 38 in the usual and recognized way.

The front wall of the furnace is provided with a door and doorway 39 giving access to the chamber 24 and the burner 32, and in a similar manner the chamber 23 has a door and doorway 41, illustrated diagrammatically only in Figure 1, giving entrance to such space and its grate for the introduction of the garbage or fuel.

35 The hot gases of combustion generated at or produced by the rotary-burner 32 in their flow through the heater to the stack or chimney come into contact with practically all of the heating surfaces of the appliance.

40 Garbage or other refuse to be consumed may be inserted through the doorway 41 in the front wall of the heater on to grate 37 where it will become dried or freed from moisture by the heat to which it is subjected, and, when sufficiently reduced in moisture

content, it will become ignited and burned supplying its heat to supplement that of the oil-burner.

As a substitute for the heat of the rotary oil-burner or to supplement the same, any suitable fuel such as coal, coke or wood may be burned on the grate 37 and its heat of combustion will be imposed on substantially the same heating surfaces as are those under the influence of the burner 32, whereby the heater may be operated economically and efficiently by heat generated in either one or both of the two chambers 23 and 24.

50 Those acquainted with this art will readily understand that this invention is not restricted to the exact mechanical details of structure presented and that these may be modified within comparatively wide limits without departure from the substance of the invention, as defined by the appended 55 claims, and without sacrifice of any of its substantial benefits and advantages. For example, if desired, more than one rotary burner or more than one grate could be employed and used as circumstances might 60 dictate.

65 I claim:

A self-contained fire-box semi water-tube heater having hollow external walls adapted to contain the fluid to be heated and having in its lower portion two compartments arranged side by side and in open communication with each other at their tops, a burner arranged to supply fuel for combustion in one compartment, and a grate in the second compartment, in combination with baffle means associated with the heater tubes to cause the products of combustion from the burner to flow over said grate and to cause the heat developed at said burner and on said grate to act on substantially the same extent of heating surfaces of the heater.

70 75 80 85 In witness whereof I have hereunto set my hand and seal.

ADOLPH T. JOHANSON. [L.S.]
